SPRING

Filed Jan. 27, 1926

FIG. 2.

FIG. 3.

Inventor
E. A. Laughlin.
By Grace C. Chandler

Attorney

UNITED STATES PATENT OFFICE.

ELMYR A. LAUGHLIN, OF OREGON, ILLINOIS.

SPRING.

Application filed January 27, 1926. Serial No. 84,222.

This invention relates to new and useful improvements in springs, and particularly to coil springs used in connection with railway car trucks, although such springs are capable of other uses.

One object of the invention is to provide a coil spring of a given length which will offer greater resistance without increasing the length of travel, than springs heretofore.

Another object is to provide a spring of this character which is formed by coiling the stock on a mandrel, and wherein the stock is formed with a longitudinal flat portion on the side next the mandrel, which permits the metal to expand into the body of the stock without the usual ribs, which would prevent the full compression of the spring, and thereby shorten its length of travel within a given space.

Another object is to provide a coil spring of this character wherein each convolution, in cross section, presents a greater transverse dimension at the side next the mandrel, with the result that when the spring is in operation the torsional strain on each individual coil will have as its center the thicker side of the stock of the spring.

Other objects and advantages will be apparent from the following description when taken in connection with the accompanying drawing.

In the drawing:

Figure 1 is a longitudinal sectional view 35 of a spring made in accordance with the present invention.

Figure 2 is a transverse sectional view through the stock from which the spring is formed, before the stock has been wound on a mandrel.

Figure 3 is a similar sectional view after having been wound on the mandrel, and showing the position of the center of the torsional strain incident to the normal operation of the spring, when under compression strain.

Referring particularly to the accompanying drawing, there is shown a coil spring each convolution of which is tapered in cross section, with the narrower portion lying at the outside of the spring, and the wider portion at the center of the spring. The narrow portion is represented by the numeral 10, and the wider portion by the numeral 11. It will be further noted that the upper and lower faces of the convolutions

are flat, and that their ends are connected by the curved portions 12 and 13, respectively. It will be further noted that the curved face 13 is formed with a flat spot or face 14, and that this flat face extends throughout the entire length of the bar stock from which the spring is formed.

In the use of a coil spring in which the convolutions are circular in cross section, the travel of the spring, toward full compression, is limited by the bulging curved adjacent faces of the said convolutions. This is inconvenient when the spring must have a definite space in which to travel, and support or resist a great load. Attempts have been made to remedy this feature by flattening the contacting faces of the convolutions. When, however, the stock is coiled on a mandrel, the portion of the stock next to the mandrel, will naturally spread, thus making the inner portions of the coils wider by the presence of a rib and thereby decreasing the length of travel of the spring. This is especially noticeable where the ends of the cross sectional areas of the convolutions are flat, as well as those which are arcuate. To overcome this defect in the coiling of the spring, and to provide a spring which will have great resistance to a load, and yet have the maximum of travel, within a given space,

I form a flat face throughout the length of the stock of the spring, before coiling the same on a mandrel. This flat face, which is shown at 14, is placed next to the mandrel. The curved portion of the stock, in which this flat face is formed, is wider than the portion at the opposite side of the coil, so that when the stock is coiled around the mandrel, the expansion of the metal, due to the compression at the mandrel, will spread into the corners 15 and 16, of the stock.

When the spring is under compression strain, the individual convolutions rotate about an axis located at 17, which is in the wider portion of the coil turn. Thus the narrower side of the coil turn rotates or rocks on the said torsional axis at 17.

While I have illustrated the flat faces of the convolutions as converging, with one of such faces at right angles to the longitudinal axis of the spring, and the other oblique thereto, it will be understood that both of the said faces may be oblique to the axis of the spring, the principal result being in producing outwardly converging faces.

In a spring wherein the flat faces are parallel, the torsional axis will be in the center of the coil turn, such being also true of a stock which is circular in cross section, whereas, the torsional axis of the present device is moved over toward the wider end of the cross sectional area of the convolution.

The flat portion of the stock serves to prevent any torsional or rolling action of the stock, on the mandrel, as the stock is being coiled therearound.

What is claimed is:

1. A coil spring each convolution of which has a cross sectional contour including opposite converging faces and opposite arcuate faces.

2. A coil spring each convolution of which has a cross sectional contour including opposite substantially flat faces and an

arcuate face, said arcuate face having an intermediate flat portion.

3. A coil spring each convolution of which has a cross sectional contour including opposite substantially flat faces and opposite arcuate faces, one of the arcuate faces having an intermediate flat portion.

4. A coil spring each convolution of which has a cross sectional contour including opposite converging faces and opposite arcuate faces, one of the arcuate faces having an intermediate flat portion.

5. A coil spring each convolution of which has a cross sectional contour including opposite substantially flat converging faces and opposite arcuate faces.

In testimony whereof, I affix my signature.

ELMYR A. LAUGHLIN.
